UNITED STATES PATENT OFFICE

LAWRENCE E. KOOS, OF TOLEDO, OHIO, ASSIGNOR, BY MESNE ASSIGNMENTS, TO THE ELECTRIC AUTO-LITE COMPANY, OF TOLEDO, OHIO, A CORPORATION OF OHIO

METHOD AND MEANS FOR FORMING COIL RETAINERS

Application filed April 18, 1919, Serial No. 290,985. Renewed May 21, 1928.

This invention relates to a method and means for constructing dynamo-electric machines, having cores with coils wound in slots. More particularly the invention relates to a 5 method and means for bending or folding the two free ends of the strip of insulation material commonly employed as a slot lining so that they constitute in effect a coil retaining means.

10 In the construction of the dynamo-electric machines having slotted cores containing windings, the winding is usually covered with one or more layers of insulation material and in the case where wire forming the winding 15 is wound in the slot by hand or machine the insulation has commonly taken the form of a thin flexible strip of fibre which was pressed into the slot previous to the winding operation. After the winding was completed a retainer 20 in the form of a strip, wedge or stick was forced into the slot at its mouth, being itself retained in position by engaging grooves formed in the walls of the slot or by the overhanging extremities of the teeth. Any excess 25 of insulation was then trimmed off.

An object of this invention is to fold or bend the insulating strip constituting the slot lining in place over the mouth of the slot.

A further object is to eliminate the retaining wedge or stick or other separate retaining means usually employed with open slots for holding the winding in place.

A further object of this invention in constructing dynamo electric machines is to index or successively move to a new position an armature or core structure by employing indexing means contacting with the armature itself, thereby moving the same to a new proper position for further operation.

40 Further objects of this invention relate to economies of manufacture and details of construction as will herein after appear from the detailed description to follow. I accomplish the objects of my invention in one instance 45 by the devices and means described in the following specification, but it is evident that the same may be put to various uses and varied widely without departing from the scope of the invention as pointed out in the appended 50 claims. A structure constituting one embodi-

ment of my invention, which may be the preferred, is illustrated in the accompanying drawings forming a part hereof in which:

Figure I is a plan view of the complete machine in this instance with a wound armature mounted thereon and in position to be operated upon. 55

Figure II is a perspective view of a wound armature with the tool for bending the slot lining shown isolated from its holder and in 60 position to enter a slot.

Figure III is a perspective view of a shoe forming a part of the bending tool.

Figures IV, V and VI are respectively, a 65 bottom plan view, an end view and a side view of the bending tool.

Figure VII is a sectional view taken on the line VII—VII of Figure IV.

Figures VIII, IX and X are sectional views taken respectively on lines VIII— 70 VIII, IX—IX and X—X of Figure VII.

Figure XI is a side view of the tool corresponding with Figure VI but showing the first shoe in the process of folding over one 75 free end of the slot lining.

Figure XII is a view similar to Figure XI but shows the tool further advanced so that the second shoe is in the process of folding free end of the slot lining.

Figures XIII and XIV are views similar 80 respectively to Figures XI and XII but show the opposite side of the tool, portions of the slot lining being cut away in each figure to more clearly show the tool.

Figure XV is an end view of the tool and 85 lining shown in Figure XIV.

Similar reference numerals refer to similar parts throughout the several views and the cross sectional views are taken looking in the direction of the small arrows. 90

In Figure I of the drawings there is shown in plan the complete machine which resembles a machine lathe. This machine includes horizontal guides 1, a head stock, 2 suitably supported, a sliding tail stock 3 and a carriage 4 slideable in said guides. Mounted between centers on the head and tail stocks 2 and 3, is shown a core structure or armature 5 on its shaft and a tool 6 operating as a contact element is carried by the carriage 4, 95 100

constituting in the embodiment disclosed moving means to operate on the armature itself.

An enlarged view of the armature is shown in Figure II where the slots in the upper half have the insulating slot lining projecting above the periphery and the tool 6 is shown in position about to enter a slot.

The tool 6 comprises a block 7 having a projecting flange portion 8 whose inner part has a curved tapered opening 9. Secured to the block 7 is a shoe 10 constituting a pilot member which as shown in Figures VI and VII has an angular portion 11 projecting downwardly and rearwardly and is separated from the block 7 by a space 12. The lower portion of the extremity of this shoe is provided with two flanges 13 which are clearly shown in Figures III and V.

The tool 6 further comprises a second block 14 and shoe 15. The block 14 is similar to the previously described block 7 except that the flange 17 corresponding to the flange 8 of block 7 is located on the opposite side. This block 14 like block 7 has a curved tapered opening 18 corresponding to the opening 9. The shoe 15 is substantially like shoe 11, previously described, and is separated from the block 14 by a space 19. The two blocks and two shoes are all secured together by a bolt 16 as shown.

In the operation of the device a wound armature having strips of sheet fibre or other insulating material between the winding and the walls of the slots with the free end portions of the insulation extending outwardly beyond the periphery is mounted between centers as shown in Figure I and the tool 6 carried by the carriage 4 is caused to advance along each slot in succession, the mounting of the armature permitting it to rotate slightly at each forward movement of the tool.

At the completion of the winding operation which may be done by hand or by machine each insulation strip 20 has its two free ends projecting from the mouth of a slot and are somewhat flared. As the tool 6 is caused to advance, the lower portion of the first shoe 11 enters a slot and rides over the winding compressing it slightly, and at the same time one free end 21 of the insulating strip engages the curved portion 9 of the block 7 by which it is bent inwardly into the opening 12. This stage of the operation is illustrated by Figure VIII. Upon further movement of the tool the end portion 21 is forced downward by the lower inclined surface of the block 7, the shoe 11 being at the same time withdrawn leaving the portion 21 within the slot and directly over the winding. Further movement of the tool brings the shoe 15 into position over the portion 21 and as this shoe advances this portion is forced down against the winding as clearly shown by Figure IX.

Simultaneously the other free end 22 of the insulation strip is bent inwardly and downwardly by the curved portion 18 of the block 14 and continued movement of the tool 6 causes this free end 22 to be tucked down into the slot over the first free end and as the shoe is withdrawn the two ends of the insulating strip take the form shown in Figure X being retained in position by the overhanging projections of the teeth.

In the actual construction of the machine the length of the tool is so proportioned relative to the length of the armature core, the number and angularity of the slots and the pitch that one forward traverse of the tool is just sufficient to rotate the armature a distance equal to the pitch so that the next slot is brought into proper alignment for the next forward traverse of the tool. The machine is constructed to operate automatically so that after being started the tool will be advanced along a slot turning in the free ends of the insulation, at the end of the forward movement it will be withdrawn to clear the armature, be returned to the initial position and again started forward along the next slot. These operations are repeated until all the slots are completed when the machine will automatically be stopped.

It will thus be seen that the winding may be effectively retained within the slots without the customary separate retaining strip or wedge or if desired a separate retainer may be employed either within or without the bent over ends of the insulation lining. By reason of the fact that this operation of folding over the free ends of the insulation lining may be accomplished by an automatic machine this feature of the production is greatly facilitated and the cost thereof reduced to a minimum.

While I have described my invention in more or less detail and as being embodied in certain precise forms I do not desire or intend to be limited thereto as on the contrary my invention contemplated broadly all proper adaptations in use changes thereof, as well as the omission of immaterial elements and the substitution of equivalents therefor as circumstances may suggest or necessity render expedient.

Having thus described my invention, what I claim as new and desire to secure by Letters Patent, is:

1. In a machine for constructing a dynamo-electric machine having a core with a slot containing a coil and a flexible lining member separating the coil from the walls of the slot, a device adapted to be moved longitudinally of the slot for bending a free end edge portion of said flexible lining inwardly over the mouth of the slot said device including a support member having a cam at the forward edge thereof and adapted to engage cooperatively an edge of a flexible lining member.

2. In a machine for constructing a dynamo-electric machine having a core with a slot containing a coil and a flexible lining separating the coil from the walls of the slot, means comprising a block having a flared opening for engaging a free edge portion of the said flexible lining and turning it inward and downward as the block is advanced along the slot. 70
- 10 3. In a machine for constructing a dynamo-electric machine having a core with a slot therein containing a winding and a flexible lining between the winding and the core, a device adapted to be moved along the slot having means for crowding down the winding and for bending inwardly one free edge of the said flexible lining into the mouth of the slot to thereby retain the winding said means including a support; a cam secured to the support with camming surfaces at the forward side thereof in the line of operative movement of the device, said camming surfaces being divergent in said forward direction. 75
- 15 4. In a machine for constructing a dynamo-electric machine having a core with a slot therein containing a winding and a flexible lining separating the winding from the walls of the slot, a device adapted to be moved along the slot comprising means for crowding down the winding and for bending inwardly one free edge of the said flexible member and means for holding down that part of the said flexible member bent by the first mentioned means, and for similarly bending the other free edge of the said flexible member against the opposite slot wall. 80
- 20 5. A device of the class described comprising means for rotatively mounting a wound core structure having diagonally arranged slots, a tool, means for supporting said tool and for moving the same along the said core structure in an axial direction and subsequently returning it to its initial position, the tool being constructed to operate upon the core structure and in its forward movement to follow the said slots thereby rotating the core structure an amount equal to the pitch of the slots. 85
- 25 6. In a device for assembling armatures having bottle shaped slots with a large winding retaining portion and a restricted neck portion, lined with insulating material; the combination with a pilot having flange and web portions adapted to enter the retaining portions and the neck portions respectively; of a folding means for turning down the edges of the lining material against the windings in the slots, said means including flange 90
- 30 and web portions corresponding to, and in alinement with, but spaced apart from the flange and web portions of the pilot, and provided with a camming surface for engaging and turning down the lining material under the flange of the folding means. 95
- 35 7. In a device for assembling armatures having bottle shaped slots with a large winding retaining portion and a restricted neck portion, lined with insulating material; the combination with a pilot having flange and web portions adapted to enter the retaining portions and the neck portions respectively; of a folding means for turning down the edges of the lining material against the windings in the slots, said means including a flange portion corresponding to and in alinement with but spaced apart from the flange portion of the pilot, and of shorter length than the length of the armature slots, and a web portion greater in transverse dimension than the web portion of the pilot and in direct alinement with but spaced apart from said pilot web, and an inclined camming surface at the extremity of both the flange and web portions of the folding means, and adjacent to the rear end of the pilot flange and web, for turning the ends of the lining material beneath the flange of the folding means. 100
- 40 8. In a mechanism for constructing dynamo-electric armatures having a core with a slot therein containing windings and a flexible lining between the winding and the core, a device adapted to be moved along a slot of said armature having means for crowding down the winding and for bending inwardly one free edge of the lining into the mouth of the slot thereby to retain the windings, said device including a support and a cam secured to and movable with the support, said cam having camming surfaces adjacent the forward edge of the device in the direction of operative movement thereof, said surfaces being divergent outwardly in the line of movement and downwardly curved. 105
- 45 9. In a mechanism for constructing dynamo-electric armatures having a core with a slot therein containing windings and a flexible lining between the winding and the core, a device adapted to be moved along a slot of said armature having means for crowding down the winding and for bending inwardly one free edge of the lining into the mouth of the slot thereby to retain the windings, said device including a support and a cam secured to and movable with the support, said cam having camming surfaces adjacent the forward edge of the device in the direction of operative movement thereof, said surfaces being divergent outwardly in the line of movement and downwardly curved; and a shoe depending from said support to the rear of said cam in the direction of movement of the device. 110
- 50 10. The method of constructing a dynamo-electric machine, having a core with a slot having a contracted mouth containing a coil and a flexible lining separating the coil from the walls of the slot, which consists in folding the free ends of the lining over each other, across the mouth of the slot, and secur- 115
- 55 60 65 70 75 80 85 90 95 100 105 110 115 120 125 130

ing one end by frictional contact with one wall of the slot.

11. The method of constructing a dynamo-electric machine having a core with a slot having contracted mouth and containing a coil and a flexible member for separating the coil from the walls of the slot which comprises bending a free end of the flexible member which is adjacent one slot wall over the mouth of the slot against the opposite wall, said end being secured across the mouth of said slot by frictional engagement with said opposite wall.

12. The method of constructing a dynamo-electric machine having a core with a slot containing a coil and a lining between the coil and walls of the slot, which comprises rolling one corner of a free end of the lining normally adjacent one wall of the slot toward the opposite wall, and progressively rolling the remainder of said end toward the opposite wall.

13. In a mechanism used in constructing a dynamo-electric machine, the combination of a support, means for movably mounting a core structure upon said support, and a movable member; the member being adapted to engage the core structure whereby the same is moved a predetermined amount with each successive movement of said member.

14. In a mechanism used in constructing a dynamo-electric machine, the combination of a support, means for movably mounting a core structure upon said support, a member and means for holding said member; said member being adapted to be moved with respect to said core structure whereby said member engages the core structure and moves the same a predetermined amount with each successive operation of said member.

15. In a mechanism used in constructing a dynamo-electric machine in combination, means for rotatively mounting a core structure, said core structure having a plurality of spaced recesses forming teeth thereon; means for indexing the core structure acting on said teeth, comprising a movable contact element and means for supporting said element; the parts being so arranged that each movement of the contact element operates to rotate the core structure a predetermined amount.

16. In a mechanism used in constructing a dynamo-electric machine, in combination, means for rotatively mounting a core structure provided with a plurality of recesses; means for performing an operation in said recesses; and means to index the core acting upon said recesses comprising a movable member; the member adapted to engage the core recesses whereby movement of said member rotates the core structure a predetermined amount.

17. In a mechanism used in constructing a dynamo-electric machine, in combination, means for rotatively supporting a core struc-

ture, said core structure having spaced recesses; means for indexing the core structure acting in the recesses comprising a movable member; means for supporting said member; manually operated means for moving the same with respect to said core and engaging means adapted to operate upon the core recesses thereby rotating the core structure an amount equal to the space between the recesses by the movement of said member.

18. In a mechanism used in constructing a dynamo-electric machine, in combination, means for rotatively mounting a core structure said core structure having a plurality of spaced recesses forming teeth thereon; means for indexing said core structure acting in said teeth, comprising a movable contact element; means for supporting said element and manually operated means for moving the same with respect to said core, the element being adapted to operate upon said teeth thereby rotating said core structure a predetermined amount.

19. The method of constructing a dynamo-electric machine having a core with a slot having a contracted mouth containing a winding and a lining between the winding and the walls of the slot which consist in forcing a free end of said lining adjacent one wall of the slot over said winding and under the projecting portion of the opposite wall.

20. In a mechanism used in constructing a dynamo-electric machine in combination, means for movably supporting a core structure having spaced recesses forming teeth thereon and means for indexing the core structure acting on said teeth comprising a movable member, a contact element carried by said member and guiding means causing said contact element to engage the teeth of said core structure moving the same an amount equal to the space between the core recesses.

In testimony whereof, I affix my signature.

LAWRENCE E. KOOS.
